INVENTOR:

Henry A. Weihman
By his acty
UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A THIMBLE.

SPECIFICATION forming part of Design No. 21,747, dated August 2, 1892.

Application filed June 8, 1892. Serial No. 435,987. Term of patent 3½ years.

To all whom it may concern:

Be it known that I, HENRY A. WEIHMANN, of the city and county of Philadelphia and State of Pennsylvania, have invented a new and original Design for Thimbles, of which

5 the following is a specification.

My design for thimbles is illustrated in the accompanying drawings, which—

Figure 1 is a side elevation of a thimble having my design applied to it; and Fig. 2 is a diagrammatic view of the same, showing the surface of the thimble flattened.

A is the upper or crown portion of the thimble and has a roughened surface.

15 B is the base of the thimble, and consists of a band about the lower portion, having upon its surface a representation of the World's Fair buildings at Chicago.

C is a plain or unornamented portion of the base portion or band B, surrounded by a scroll-border D.

What I claim is—

The design for a thimble, comprising the upper roughened crown, the lower encircling band having the representation of the World's Fair buildings at Chicago, and an unornamented portion C thereon, bounded by the scroll outline D.

In testimony of which invention I have hereunto set my hand.

HENRY A. WEIHMANN.

Witnesses:

ERNEST HOWARD HUNTER,
C. M. DIETTERICH.
